US00D947837S

(12) **United States Design Patent** (10) **Patent No.:** **US D947,837 S**
Wall et al. (45) **Date of Patent:** **** Apr. 5, 2022**

(54) **ELECTRONIC DEVICE**

(71) Applicant: **Amazon Technologies, Inc.**, Seattle, WA (US)

(72) Inventors: **Timothy Eli Wall**, Mill Valley, CA (US); **Marc Rene Walliser**, San Francisco, CA (US)

(73) Assignee: **Amazon Technologies, Inc.**, Seattle, WA (US)

(**) Term: **15 Years**

(21) Appl. No.: **29/717,072**

(22) Filed: **Dec. 13, 2019**

Related U.S. Application Data

(62) Division of application No. 29/610,134, filed on Jul. 10, 2017, now Pat. No. Des. 873,265, which is a division of application No. 29/560,832, filed on Apr. 11, 2016, now Pat. No. Des. 795,249.

CLAIM

The ornamental design for an electronic device, as shown and described.

DESCRIPTION

FIG. 1 is a front perspective view of an electronic device showing the new design;

FIG. 2 is a back perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The broken lines depict portions of the electronic device that form no part of the claimed design.

1 Claim, 8 Drawing Sheets
